G. F. GODLEY,
LUBRICATOR FOR JOURNALS,
APPLICATION FILED APR. 8, 1915.

1,193,136.

Patented Aug. 1, 1916.

UNITED STATES PATENT OFFICE.

GEORGE F. GODLEY, OF PHILADELPHIA, PENNSYLVANIA.

LUBRICATOR FOR JOURNALS.

1,193,136.

Specification of Letters Patent.

Patented Aug. 1, 1916.

Application filed April 8, 1915. Serial No. 19,929.

To all whom it may concern:

Be it known that I, GEORGE F. GODLEY, a citizen of the United States, residing at Philadelphia, in the county of Philadelphia and State of Pennsylvania, have invented a certain new and useful Lubricator for Journals, of which the following is a specification, the same being an improvement upon the lubricator described and claimed 10 in my United States Patent No. 770,684, dated September 20, 1904.

The principal object of the present invention resides in the providing of a lubricator for journals in which the parts are designed 15 and co-operatively arranged to produce a more efficient and commercially valuable lubricator than that disclosed in my aforesaid patent.

The invention consists of the improvements hereinafter described and finally claimed.

The nature, characteristic features and scope of the invention will be more fully understood from the following description 25 taken in connection with the accompanying drawings forming part hereof and in which:

Figure 1, is a view in longitudinal section, of a journal box equipped with a journal lubricator embodying the invention; Fig. 2, 30 is a perspective view of a piece of absorbent material used in the journal lubricator. Fig. 3, is a similar view of the same properly formed for use. Fig. 4, is a top or plan view of a somewhat modified form of journal lubricator detached; and Fig. 5, is a view in longitudinal section thereof.

In the drawings and referring to Figs. 1, to 3 inclusive, the journal box 10, is of the type designed to contain oil in the bottom 40 thereof, and the rear wall 11, of the box is provided with an integral, laterally disposed horizontal shelf 12, to prevent the splashing of oil against a dust guard (not shown) located within compartment 13.

45 The lubricator of the invention is designated 14, and is located within the oil reservoir 15, beneath the journal 16. The lubricator is provided with an absorbent material holder, embracing a plate 17, conforming to 50 the shape of the journal and has formed integral therewith a depending sleeve 18, the bottom of which is free of the journal box bottom. In practice, the holder is formed of sheet metal struck up into the form shown. 55 Fitted to the upper face of the plate 17, is absorbent material 19, preferably felt.

This material as shown in Fig. 2, is rectangular, unapertured and is quite thick. It is first separated marginally considered into two layers, then the free marginal ends of one section are gathered together to form a sleeve 20, which sleeve is then extended down through the sleeve 18, so as to impinge against the bottom of the journal box and closely hug the side walls of sleeve 18. In 60 practice the absorbent material of the upper layer is left intact and the lower layer is detached at all edges but left integral with the central portion of the upper layer, see Fig. 1. The upper layer above described is 65 secured as by rivets 21, or equivalent fastening mediums to the outer ends of the plate 17, the marginal edges of the said material being extended slightly beyond the edges of plate 17, as shown so that the collars of 70 journal 16, may be lubricated. Thus fitted to place, the said material is secured against being displaced by the revolving of the journal 16, the advantages of which are 75 obvious. A spiral spring 23, or equivalent 80 means, is present for maintaining the lubricator in operable position with respect to the journal 16.

In Figs. 4, and 5, the pliable material 21, is apertured as at 22, and the depending 85 sleeve is omitted. In lieu thereof a piece of coiled absorbent material 23, is fitted within the sleeve 18, which material extends from the bottom of the journal box to the top of the absorbent material 21, see Fig. 5.

90 In practice, best results are obtained by first submerging an oiler of either of the above described constructions in a bath of oil and then fitting the same to place beneath a journal. The bath of oil serves to exclude 95 the penetration of air to the absorbent material. By the exclusion of air, a vacuum is maintained in the sleeve 18, of the oiler, the advantages of which are well known. Further, by reasons of such bath the absorbent material more quickly feeds oil to the journal.

100 What I claim is:

1. A lubricator of the class described embracing an apertured plate provided with a depending sleeve, non-apertured absorbent material fitted to said plate and integrally extended down within said sleeve to conform to the shape thereof and provide an oil well, means for securing the said material to said plate and means operative for yieldingly 110 supporting said plate.

2. A lubricator of the class described embracing an apertured plate provided with a depending sleeve, non-apertured absorbent material, the marginal edges of which are loosened and the lower section folded to form a sleeve which is extended down into the first mentioned sleeve to conform to the shape thereof and provide an oil well, means for securing the outer edges of said top section to the plate, and means operative for yieldingly supporting said plate.
- 5
3. In combination a journal box constructed to contain oil in the bottom thereof, a journal, an apertured plate conforming to the shape of the journal provided with a
- 10
- 15
- depending sleeve, absorbent material fitted to said plate so as to extend marginally beyond the plate, absorbent material within the sleeve, rivets for securing the absorbent material adjacent the plate corners and means operative between the bottom of the said box and plate for yieldingly maintaining said plate in contact with the journal.
- 20

In testimony whereof, I have hereunto signed my name in the presence of two witnesses.

GEORGE F. GODLEY.

Witnesses:

WILLIAM J. JACKSON,
AGNES C. CASKEY.
